[57] CLAIM

The ornamental design of a seat plate, as shown and described.

DESCRIPTION

FIG. 1 is a top elevational view of the seat plate showing my new design;

FIG. 2 is a rear view of the seat plate of FIG. 1;

FIG. 3 is a front view of the seat plate of FIG. 1;

FIG. 4 is a bottom elevational view of the seat plate of FIG. 1;

FIG. 5 is a right side view of the seat plate of FIG. 1;
FIG. 6 is a left side view of the seat plate of FIG. 1; and,
FIG. 7 is a perspective view (with the seat plate flipped over)
of the seat plate in FIG. 1; showing in more detail the raised
portion immediately in front of the front bracket, and the
welding which goes only along the outside of the front
bracket.
